UNITED STATES PATENT OFFICE.

JAMES A. BROGAN, OF LAWRENCE, AND MEYLERT BRUNER, OF NEWTON, MASSACHUSETTS.

1,132,430.

Specification of Letters Patent.

Patented Mar. 16, 1915.

Application filed October 2, 1914. Serial No. 864,645.

To all whom it may concern:

Be it known that we, JAMES A. BROGAN and MEYLERT BRUNER, citizens of the United States, residing, respectively, at Lawrence, 5 in the county of Essex and State of Massachusetts, and at Newton, in the county of Norfolk and State of Massachusetts, have invented a new and useful Improvement in Puzzles, of which the following is a specification.

The present invention relates to puzzles.

The object of the invention is to produce a puzzle which will have an intricate mode of operation and be solved with difficulty. 15 To the accomplishment of this object, and such others as may hereinafter appear, the features of the invention relate to certain devices, combinations and arrangements of parts, hereinafter described and then set forth broadly and in detail in the appended claims, which possess advantages which will be apparent to those skilled in the art.

The various features of the present invention will be readily understood from an 25 inspection of the accompanying drawing illustrating the preferred embodiment of the invention, in which,

Figure 1 is a plan of the puzzle with the rolls having the characters thereon arranged 30 in the slots of the rotatable disk in a predetermined order, namely, to indicate the term "New door," Fig. 2 is a plan showing the puzzle with the rolls in the position to which they are brought when the puzzle has been 35 solved, and Fig. 3 is a central sectional elevation of Fig. 2.

In the illustrated embodiment of the invention the puzzle comprises a flat plate 1 having a central dished cavity 2 formed 40 therein. Mounted to rotate on a rivet 3 is a disk 4 having a series of eight slots 5 formed in its periphery. The disk normally carries a series of eight rolls 6 arranged in the slots 5 of the disk. The top and bottom faces 45 of each roll consist of disks 7 which overlap and slide on the top and bottom faces of the disk 4 respectively. The disks 7 are separated from each other by a slender cylindrical neck 8 which is loosely embraced by 50 the slots in the disk. Seven of these rolls are provided with characters and the rolls

are arranged in a predetermined order so that these characters indicate the term "New door." We have discovered that the characters comprising this term are incapable of being arranged so that they indicate one word, but that they may be so arranged that they indicate the term "One word." 55 This discovery forms the basis of the puzzle. When the puzzle is given to a person with 60 instructions to solve it by arranging the characters so that they indicate one word the person naturally shifts the rolls around in an effort to arrange them in such manner that they indicate but one word. As this 65 is impossible considerable amusement is caused when it is discovered that the characters may be shifted so that they indicate the term "One word" which is the answer to the puzzle.

In order to permit the ready shifting of the rolls the cavity 2 is connected by a longitudinal slot 9 to a cross slot 10. The walls of these slots embrace the neck 8 of the rolls so that they are readily shifted into and out 75 of the rotatable disk 4 to and from the slot 10.

It will be apparent to those skilled in this class of puzzles that changes may be made in the details of structure the described and 80 illustrated embodiment thereof being intended as an exploitation of its underlying essentials, the features whereof are definitely stated in their true scope herewith.

What is claimed as new, is:—

1. A puzzle having a body portion provided with movable elements bearing characters normally arranged to indicate the term "New door," said movable elements adapted to be shifted to form the term "One 90 word."

2. A puzzle having a body portion provided with movable elements bearing the characters N, E, W, D, O, O, R.

3. A puzzle having in combination, a 95 plate, a disk having a slotted periphery rotatably mounted thereon, a plurality of rolls bearing the characters N, E, W, D, O, O, R, normally arranged in the slots of the disk in a predetermined order, and means permitting the rolls to be removed from the disk and arranged on the plate, said rolls 100

being capable of arrangement to indicate the term "One word."

4. A puzzle, having in combination, a plate, a disk having a slotted periphery rotatably mounted thereon, and a plurality of rolls having characters thereon, said rolls bearing characters normally arranged to indicate the term "New door," and means per-

mitting the rolls to be shifted to form the term "One word."

JAMES A. BROGAN.
MEYLERT BRUNER.
